UNITED STATES PATENT OFFICE.

HERBERT G. UNDERWOOD, OF NEW YORK, N. Y.

INTERNAL-COMBUSTION ENGINE.

No. 879,989.

Specification of Letters Patent.

Patented Feb. 25, 1908.

Application filed October 25, 1906. Serial No. 284,271.

To all whom it may concern:

Be it known that I, HERBERT G. UNDERWOOD, a citizen of the United States, residing at New Brighton, borough of Richmond, city of New York, State of New York, have invented certain new and useful Improvements in Internal-Combustion Engines, of which the following is a specification, reference being had to the accompanying drawings, forming a part hereof.

This invention relates particularly to igniting devices for internal combustion engines and has for its object to increase the certainty of ignition while making it unnecessary to employ either an electric igniter or a torch.

The invention will be more fully explained hereinafter with reference to the accompanying drawings in which it is illustrated as embodied in a convenient and practical form.

The single figure of the drawing is a view in vertical section of the lower portion of an engine showing the arrangement of the igniting devices.

In the engine represented in the drawing the working cylinder *a* is set vertically and is suitably supported as by struts *b*.

*a*⁵ is a suitable supply passage terminating in a supply port *a*⁶, through which a combustible mixture is supplied to the working cylinder *a* to be compressed therein as the said piston descends, and *a*⁷ is a suitable exhaust port, these parts being elements commonly present in internal combustion engines operating upon a two-stroke cycle to which class the engine illustrated belongs.

For the ignition of the charge in the explosion chamber use is made of the property possessed by certain bodies, notably finely divided platinum, of effecting the ignition of the gases to which they are exposed. Ordinarily these bodies lose the property referred to after use for a considerable time, from causes which are not necessary to be more particularly referred to herein, but it has been found in the development of the present invention that under the conditions to which said bodies are exposed in the operation of internal combustion engines, the desired quality is retained unimpaired, particularly if the bodies are so placed as to prevent the accumulation of carbon thereon.

It is found that the distribution of gas-occluding material at different points in the cylinder head secures, under the influence of the compression of the gaseous charge in con-

tact with the occluding material, certainty of operation, so that ignition takes place without fail whenever a proper mixture of the gaseous material is compressed in the working cylinder. Furthermore, through the support of the occluding material at some distance from the extremity of the cylinder head and perhaps the action of the explosion, the occluding material is kept clear and free from carbon and retains its peculiar property for a long time in actual use.

On the cylinder head *o* is supported a plate *p*, insulated from the cylinder head by lugs *p'* which hold it away therefrom and held from jumping up by pins or screws *p*². On the plate *p* or on the cylinder head, are formed tubular supports *q*, *q'*, preferably having somewhat contracted mouths *q*³, while the tubular supports *q* may open through the plate *p* to communicate with the space between it and the cylinder head. The occluding material, indicated at *n*³, is preferably supported just within the mouths of the tubular supports *q*, *q'* and during the compression of the charge in the working cylinder the occluding bodies are thus exposed to currents of the mixture and the action of such bodies in effecting the ignition of the mixture is more prompt and certain than is the case when such bodies are located in a body of the mixture which has no movement at or near the instant of greatest compression. Obviously the tubular supports might be located otherwise than as shown in Fig. 4, which illustrates merely a convenient arrangement thereof. The shell of the tubular support *q'* is shown as extended through the head *o* for the application of a torch igniter if desired at any time.

I claim as my invention:

1. In an internal combustion engine of the compression type, the combination of a working cylinder; a piston; a tubular support carried by the cylinder head and projecting into the clearance space, said support being in permanently open communication at two points remote from each other with the interior of the working cylinder; and a gas occluding body located within said support and adjacent the upper end thereof.

2. In an internal combustion engine of the compression type, the combination of a working cylinder; a piston; a tubular support carried by the cylinder head and projecting into the clearance space, said support being in permanently open communication at both

its ends with the interior of the working cylinder; and a gas occluding body located within said support and adjacent the upper end thereof.

- 5 3. In an internal combustion engine of the compression type, the combination of a working cylinder; a piston; a plate within the cylinder carried by the cylinder head and insulated therefrom; a tubular support carried
10 by said plate and projecting into the clearance space, said support being in perma-

nently open communication at both its ends with the interior of the working cylinder; and a gas occluding body located within said support and adjacent the upper end thereof. 15

This specification signed and witnessed this 24th day of October, 1905.

HERBERT G. UNDERWOOD.
